UNITED STATES PATENT OFFICE.

FREDERICK C. DAVIS, OF SAN FRANCISCO, CALIFORNIA.

SUPPORT AND BACKING FOR TERRA COTTA OR OTHER FACING BLOCKS.

Application filed September 24, 1923. Serial No. 664,360.

This invention relates to supports and backing for terra cotta and other facing blocks, and the object is to improve the present methods of supporting and holding

5 in place terra cotta, artificial stone, cement or concrete blocks, etc. in front of cement or concrete wall surfaces previously installed, such as reinforced concrete, concrete, cement or grout around structural steel or 10 other metal.

This object I accomplish by the provision of five new units to be used individually or collectively.

The first unit consists of a U-shaped staple 15 embedded in the wall on frequent horizontal centers and serving the new and useful duty of receiving the vertical load from the usual adjustable hangers hooked around a horizontal rod or pin. This U-shaped staple also 20 acts as a dowel support to the added load above.

The second unit consists of grooves or ledges formed on the concrete face of the wall to help resist the shear of the vertical 25 load.

The third unit consists of dowels on frequent centers embedded in the wall. These dowels receive the vertical load from above and from hangers hooked around horizontal 30 rods or pins below as well as to dowel the concrete grout to the face of the concrete wall, etc.

The fourth unit consists of a combination of a loop, a brace, a dowel, and an anchor 35 embedded in the wall on frequent centers, and usually referred to as a "loop-brace-anchor". The principal use of this loop-brace-anchor is to horizontally tie, hook or anchor the blocks to the concrete face of the 40 wall.

The fifth unit consists of extensions of wires or rods to be placed over the above-mentioned dowels, anchors and U-shaped staples and thus act as additional ties and 45 reinforcements in the concrete grout.

One form which my invention may assume is exemplified in the following description and illustrated in the accompanying drawing, in which

50 Fig. 1 shows a vertical section of a portion of a building embodying my invention.

Fig. 2 shows a perspective view of a portion of the same.

Fig. 3 shows a vertical section of the concrete wall and wooden forms.

Fig. 4 shows a horizontal section through the wall.

The concrete wall is indicated at 10 and the terra cotta facing is indicated at 11. The wall is made with grooves or depressions 14 through the use of the type of wooden forms indicated at 13 in Fig. 3. The purpose of so grooving the wall is to provide a better bond with the grout backing 12 between the terra cotta blocks and the concrete wall.

At the time of installing the forms for the concrete wall I arrange upon the wooden forms U-shaped staples 16, grooves 14, dowels 15 and loop-brace-anchors 17. The U-shaped staple 16 is adapted to receive a hanger 25 which may or may not extend through a notch 26 in the terra cotta block and has a hooked end 19 to engage a rod 20, the rod being extended through horizontal holes in the webs and ends of the terra cotta blocks. This hanger 25 may be either adjustable through a nut and washer 21 threaded on to its upper end or may be a plain rod without threads, nut or washer, and extend up through the U staple far enough so that the adhesion of the cement grout, when set, will hold this hanger and its load in place. The extended end of the dowel 15 projects into or toward the cellular openings in the blocks and in some instances these dowels also support hook-shaped hangers 22, which in turn are used to support lintels 23 by engagement with horizontal rods 24, and, in other instances, by engaging the member 22 with the holes in the blocks.

The loop-brace-anchor 17 is shown in detail in Fig. 4 and consists of a wire bent double near the center and formed with a loop at one end. This loop-brace-anchor is inserted in an opening in the wooden form, usually from the outside, and, when driven home, the part to be embedded in the concrete may or may not spread apart somewhat in the shape of a V, leaving a loop and one end projected from the concrete when later placed and thus provide a pin or dowel anchor and a loop staple for horizontally anchoring the blocks to the wall.

Wires or rods 18 are also hung over these U-shaped staples 16, dowels 15 and loop-

brace-anchor 17 and extend into or near the cellular spaces in the blocks for forming additional reinforcement for shear and are usually referred to as "extensions".

- 6 Modern practice and protection against damage in case of fire require that built-up girders and I-beams be enclosed with reinforced concrete and this requirement makes it impossible to use an iron plate or an angle 10 iron as a shelf to support terra cotta, as they both cut in two the reinforced concrete fire-proofing.

Furthermore, a shelf angle iron attached by bolts embedded either in the fire proofing around beams and girders or in reinforced concrete spandrels is difficult to construct and is unsatisfactory on account of the bolts not registering with the holes in the angle iron when the latter are installed. As a 20 result, these bolts are often loosened in the concrete when struck with a sledge hammer to get them to register with the holes in the angle iron. These shelf angle irons are usually either a little too high or too low and the terra cotta often has its structural strength cut way in order to adjust itself to the position of the shelf angle iron. Further difficulty is found in securely anchoring the terra cotta below to the iron plate or angle iron above, both of which prevent the grout from getting down into the terra cotta below to embed the metal anchors for stability and to insure against future rusting out of the anchors and angle iron or iron plates.

35 The **U** staples with the adjustable hangers 25 holding up the continuous horizontal rods 20 are comparatively light in weight, less expensive, easily installed, positive in action, permit definite solid grouting with concrete, and therefore are dependable structural supports and protection against rust. Furthermore, they overcome the many difficulties encountered with shelf iron plates and angle irons, all as above recited.

45 Since there cannot be a dependable bond between the vertical faces of concrete which are not poured at the same time, neither can it be expected that there will be a dependable bond between grout backing of terra 50 cotta and the vertical face of concrete surfaces of beams and girders which has been poured weeks previously. The grooves and ledges of the present invention make a dependable bond and successfully resist the 55 vertical shear between the older concrete surfaces and the grout which mechanically supports the terra cotta.

The dowels can easily be placed in the 60 wooden forms by the laborers of the contractor for the concrete, and, as these dowels are embedded in the concrete of beams and girders and later enclosed in the grout, the terra cotta and the grout and the concrete structure thereby become one monolithic 65 unit.

In prior practice it is usual to employ tie rods or wires which are loose at each end, one end being turned down into the terra cotta and the other end hooked into a metal loop embedded in the concrete. Such an anchor 70 requires more work to shape and place and is difficult to make rigid. This difficulty is overcome by my new device which comprises a loop, a dowel, a brace and an anchor easily inserted in the wooden forms and 75 securely embedded in the reinforced concrete, including beams, girders, spandrels, piers, walls, etc. The loop serves as a staple to hold the temporary tie wire from the terra cotta and later to hold a loose anchor or 80 anchors. The single or double arm when fastened into the anchor hole of the terra cotta acts as a dowel, a brace, and as a rigid anchor to hold the terra cotta firmly 85 in line while being filled with grout, concrete or brick, or left hollow.

The metal wire or rod extensions which are hung over the dowels, staples or anchors and which extend into the cellular spaces of the terra cotta, or elsewhere, act as an additional metal reinforcement in the concrete 90 and grout and materially assist to neutralize the diagonal and vertical components of the load developed by the weight of the terra cotta, thus more fully carrying out the 95 reinforced concrete method of supports.

Having thus described my invention, what I claim and desire to secure by Letters Patent is:

1. In a building construction of the class 100 described, a concrete wall having grooves on the face thereof, a plurality of anchoring members embedded in said wall and having portions projecting beyond the face thereof, facing blocks carried by said anchoring 105 members in spaced relation to the concrete wall face, concrete grout between the facing block and concrete wall to engage the facing blocks and the grooves on the face of the concrete wall, and means for attaching the 110 anchoring means to the said facing blocks.

2. In a building construction of the class 115 described, a concrete wall having grooves on the face thereof, a plurality of anchoring members embedded in said wall and having portions projecting beyond the face thereof, facing blocks carried by said anchoring members in spaced relation to the concrete wall face, concrete grout between the facing block and concrete wall to engage the facing 120 blocks and the grooves on the face of the concrete wall, means for attaching the anchoring means to the said facing blocks, said last mentioned means including rods extending through openings in the facing 125 blocks and bolts connecting said rods with the anchoring members in the wall.

3. In a building construction of the class 130 described, a concrete wall having grooves on the face thereof, a plurality of anchoring

members embedded in said wall and having portions projecting beyond the face thereof, facing blocks carried by said anchoring members in spaced relation to the concrete wall face, concrete grout between the facing block and concrete wall to engage the facing blocks and the grooves on the face of the

concrete wall, means for attaching the anchoring means to the said facing blocks, said means including hooks engaging openings 10 in the facing blocks and in turn hooked onto the anchoring members in the wall.

FREDERICK C. DAVIS.
